UNITED STATES PATENT OFFICE

138,709

DESIGN FOR A HOUSING FOR LUBRICANT DRUMS OR THE LIKE

Charles W. Ginter, Bryan, Ohio, assignor to The Aro Equipment Corporation, Bryan, Ohio, a corporation of Ohio

Application December 31, 1943, Serial No. 112,132

Term of patent 14 years

(Cl. D52—2)

To all whom it may concern:

Be it known that I, Charles W. Ginter, a citizen of the United States, and a resident of Bryan, in the county of Williams and State of Ohio, have invented a new, original, and ornamental Design for a Housing for Lubricant Drums or the like, of which the following is a specification, reference being had to the accompanying drawing forming a part thereof:

Figure 1 is a perspective view of a housing

for lubricant drums or the like, showing my new design;

Figure 2 is a front elevational view;

Figure 3 is a top plan view; and

Figure 4 is a side elevational view thereof.

I claim:

The ornamental design for a housing for lubricant drums or the like, substantially as shown.

CHARLES W. GINTER.
